UNITED STATES PATENT OFFICE.

WILLIAM HURD, OF WARREN, INDIANA, AND WILLIAM WRIGHT, OF FRANKLIN, PENNSYLVANIA.

FRAME FOR PUMPING POWERS.

No. 810,945.

Specification of Letters Patent.

Patented Jan. 30, 1906.

Application filed October 15, 1904. Serial No. 228,653.

To all whom it may concern:

Be it known that we, WILLIAM HURD, residing at Warren, in the county of Huntington and State of Indiana, and WILLIAM 5 WRIGHT, residing at Franklin, in the county of Venango and State of Pennsylvania, citizens of the United States, have invented certain new and useful Improvements in Frames 10 for Pumping Powers, of which the following is a specification, reference being had therein to the accompanying drawings.

Our invention relates to an improved pumping power of the belt-driven type, the construction of which will be fully understood from the following specification, reference being had to the accompanying drawings, which form a part hereof, and in which—

Figure 1 is a perspective view of our improved power. Fig. 2 is a plan view of the upper bearing. Fig. 3 is a plan view of the lower bearing. Fig. 4 is a vertical section of an anchor-block, showing a portion of the tubular braces and the tie-rods which we employ.

The novelty of the pumping power here shown lies in the construction of the bearings for the vertical shaft to which the belt-wheel and eccentrics are attached; also, in the construction of the anchor-blocks and the method of attaching said bearings thereto.

The construction of our power is substantially as follows: A lower bearing 1 has a box 1' thereon for the reception of the lower end 35 of the vertical shaft 2, which lower bearing is preferably of a cylindrical form, with a square base-plate which has at each corner a hole for the reception of foundation-bolts. Upon the periphery of the cylindrical portion of the 40 lower bearing are three radially-disposed bosses 3 3 3, each having a recess 4 therein for the reception of a tie-rod 5. The bosses 3 are of such a diameter as to readily enable them to enter a tubular brace 6 of a specific diameter. The upper bearing 7 is adapted 45 to the reception of the upper end of the vertical shaft and is also preferably of a cylindrical shape, having three equally-disposed

radial bosses 8 8 8, each having a recess 9 therein for the reception of a tie-rod 10. Said 50 bosses 8 are at their ends adapted to enter the tubular braces 11 11 11. Each set of tubular braces 6 and 11 receives at their outer ends the bosses 12 and 13 upon the anchor-blocks 14 14 14, through which blocks the rods 5 and 10 also pass. Thus it will be noted that an upper and a lower brace are arranged in pairs, which are positioned in vertical alignment, and that one anchor-block receives both of said braces. The tie-rods are threaded at each end, and after the tubular braces are in position nuts upon said ends are firmly screwed up, which holds the bearings and the blocks securely and rigidly together, forming 60 a strong and durable power.

From an inspection of the drawings it will be noted that both sets of braces have a downward slant and that the anchor-blocks are located in a horizontal plane somewhat below the lower bearing. This construction greatly 70 lessens the possibility of the settling of the lower bearing.

The anchor-blocks are not connected to each other by any horizontally-disposed members, as is the case in all other powers of this 75 class. Hence it requires a much simpler and less expensive foundation, which foundation consists only of a suitable pier for the lower bearing and one for each of the anchor-blocks to which they are each suitably bolted.

In Fig. 1 is shown a belt-wheel 15, which is keyed to the vertical shaft 2 in the usual way. An eccentric 16 of the usual type employed in pumping powers is also keyed to the shaft.

Having thus described our invention, what 85 we claim as new, and desire to secure by Letters Patent, is—

1. In a frame for pumping powers, a lower bearing, adapted to the reception of the lower end of a vertical shaft, an upper bearing, adapted to the reception of the upper end of a vertical shaft, there being radially-disposed bosses on each of said bearings, arranged in vertically-alined pairs, a tubular brace for each of said bosses, and receiving the same at 90 one end, an anchor-block adapted to the at- 95

tachment of the other end of each vertically-alined pair of braces, a tie-rod passing through each of said braces and secured at one end in one of the bosses aforesaid and at the other end in its respective anchor-block.

2. In a frame for pumping powers, an upper bearing and a lower bearing, and the anchor-blocks, in combination with the tie-rods and tubular braces, arranged in vertically-alined pairs and connecting said bearings and said anchor-blocks.

In testimony whereof we affix our signatures in the presence of two witnesses.
